UNITED STATES PATENT OFFICE.

JOHN W. ALFRED, OF JEFFERSONVILLE, INDIANA.

ALARM-LOCK.

1,151,149.

Specification of Letters Patent. Patented Aug. 24, 1915.

Application filed February 8, 1915. Serial No. 5,527.

To all whom it may concern:

Be it known that I, JOHN W. ALFRED, a citizen of the United States, residing at Jeffersonville, in the county of Clark and State 5 of Indiana, have invented certain new and useful Improvements in Alarm-Locks, of which the following is a specification.

The door which is the subject matter of the present application for patent is designed more particularly for use in banks to 10 detain persons committing unlawful acts, or wherever a door of this or a similar description would be effective.

In carrying out the invention, there is provided a door-closing means which is controlled from a distance, together with an audible alarm or signal device which is sounded when the door shuts, thus giving 15 a warning to the watchman, guard or other persons to take proper measures for apprehending the person or persons who may be 20 shut up in the room which is controlled by the door.

In order that the invention may be better understood, reference is had to the accompanying drawing, in which an elevation of the door, partly in section, is shown, with the invention applied thereto, certain parts 25 being shown largely diagrammatic.

Referring specifically to the drawing, 5 denotes a sliding door provided with a suitable closing means, such as a weight 6 carried by a line 7 connected to the door, and passing over a guide pulley 8. Any other 35 means may be provided for automatically closing the door after a catch or other device which holds the door open, is released. A catch 9 is shown, the same being on the armature lever of an electro-magnet, said catch 40 being located to engage a keeper 11 secured to the rear portion of the door. The magnet is connected to a battery 12, or other suitable source of electric energy, and is controlled by a push-button 13 or other suitable circuit 45 closer. This push-button may be located at any convenient place within easy reach of the bank teller or other person, so that he may effect the automatic closing of the door without leaving his accustomed place.

It will be evident that various other devices 50 may be employed for effecting an automatic closure of the door from a distance,

and the invention is not limited to the particular devices described hereinbefore.

The bottom edge of the door slides in a 55 guide groove 14 in the floor, with no projection above the surface of the floor.

In order that an alarm may be given when the door closes, there is mounted in a mortise 15 in the forward edge of the door 5, a bell 60 16. In the mortise is also mounted a pivoted latch 17 shaped at one end to hook over a keeper 18 on the jamb 19 against which the door closes, and having connected to its other end a resilient stem 20 carrying a bell-hammer 21. The latch is so located that when it swings down as it snaps over the keeper, the hammer is carried against the bell to sound the same. A spring 22 connected to the latch holds it normally in such 65 a position that the bell-hammer touches the bell. Thus, when the latch strikes its keeper it rises against the tension of the spring, and the spring then snaps it down behind the keeper, the last movement of the latch carrying the bell-hammer against the bell to 70 sound the same.

While the preferred embodiment of the invention has been shown, it will be evident that many changes and modifications in the 75 structural details shown and described may be made without departure from the spirit and scope of the invention as claimed hereinafter.

I claim:

The combination with a door and frame, of a pivoted latch and a bell carried by the door, the forward edge of the door having a mortise in which the latch and the bell are mounted, a resilient stem connected to one 90 end of the latch and carrying a bell-hammer, a spring connected to the latch for swinging the same in a direction to carry the hammer against the bell, and a keeper on the door frame engageable by the latch, the latch 95 having a swinging movement to engage the keeper.

In testimony whereof I affix my signature in presence of two witnesses.

JOHN W. ALFRED.
